COIN CONTROLLED VENDING APPARATUS

Fairfield W. Hoban, New York, N. Y., assignor, by
mesne assignments, of one-half to himself and
one-half to James H. Martin, Chicago, Ill., as
tenants in common

Application February 25, 1941, Serial No. 380,454

20 Claims. (Cl. 194—10)

My invention relates generally to apparatus for vending or dispensing packaged commodities such as cigarettes, chewing gum, razor blades, candy, and the like.

One object of my invention is the provision of a vending apparatus of the character described which is electrically operated and comprises coin or check registering and counting mechanism, article selecting mechanism, and article ejecting mechanism.

Another object of the invention is to provide an apparatus of the character specified in which the electrically operated means is controlled by the insertion of dimes and nickels totaling in amounts fifteen or twenty cents only.

Further said invention has for its object to provide an apparatus of the character specified in which the selective elements thereof include means for determining the coin totalization at which the apparatus is to be operated.

Further, said invention has for its object to provide an apparatus of the character specified in which the selective elements thereof are co-ordinated with means for completing the control circuits to impart movement to said means in one direction or the other according to the control circuit to be closed.

Another object of the invention is to provide an apparatus of the character specified in which means is provided under the control of the operator for returning coins to the operator and under control of the apparatus for retaining the coins inserted, one operation preventing the other operation, and both operations serving to cause the resetting of the coin totalizing mechanism.

Another object of the invention is to provide an apparatus of the character specified in which the ejecting elements thereof are mounted upon a common movable support to be selectively projected by the operation of the apparatus.

Another object of the invention is to provide an apparatus of the character specified in which the respective selector elements, each serving to control the circuit of the proper totalization, are each utilized to control the projection of the ejecting element corresponding thereto upon actuation of said support.

Another object of the invention is to provide an apparatus of the character specified in which the ejecting elements are actuated by a snap action.

Another object of the invention is to provide an apparatus of the character specified in which the snap action mechanism is controlled by the

corresponding selective element serving as an abutment upon one movement of the support and by a fixed abutment upon completion of the reverse movement of the support.

5 Another object of the invention is to provide an apparatus of the character specified in which each selector element upon actuation thereof to start the operation is locked in depressed position to enable the same to function as a fixed abutment for controlling the snap mechanism of the corresponding ejecting element.

Another object of the invention is to provide an apparatus of the character specified in which the ejector support is mounted for swinging movement to be actuated by the rotatable motor through a crank mechanism, whereby to insure free and easy operation thereof.

Another object of the invention is to provide 20 an apparatus of the character specified in which means for dispensing supplemental or auxiliary articles such as matches, is associated with the apparatus to be positively actuated by the motor for ejecting the article.

Another object of the invention is to provide an apparatus of the character specified in which the auxiliary or supplemental dispensing means is actuated through a motor driven member performing a resetting operation.

25 Another object of the invention is to provide an apparatus of the character specified in which the auxiliary ejecting means operates during two successive operations of the motor to eject the articles alternately from two article holding compartments while insuring occurrence of the resetting operation upon each cycle of operation of the motor.

Another object of the invention is to provide 30 an apparatus of the character specified in which the coin counter or totalizer is capable of being restored or reset by simple mechanism actuated both upon the coin returning operation and upon the dispensing operation.

Another object of my invention is the provision 35 of an apparatus of the character described which is of relatively simple construction and of relatively few parts, and the cost of manufacture and assembly of which is substantially reduced over vending machines known in the art.

40 My invention, for purposes of illustration only, will be described in relation to a cigarette package vending machine. It will be obvious from the following description of this illustrative embodiment that, changed only to conform to the

size and shape of any other commodity, packaged or otherwise, my invention may be modified to function in an identical manner to dispense any commodity without departing from my invention and my invention is to be limited only in accordance with the claims appended.

In the drawings annexed hereto, forming a part hereof,

Figure 1 is a front elevational view of the lower portion of one form of device constructed according to and embodying my invention, the enclosing cabinet being removed to show the operating mechanism;

Fig. 2 is an elevational view of the right side thereof, as viewed from the front, Fig. 1;

Fig. 3 is an enlarged vertical section along the line 3—3 of Fig. 1;

Fig. 4 is an enlarged section along the line 4—4 of Fig. 1;

Fig. 5 is an elevational view of the left side of the mechanism, as viewed from the front, Fig. 1;

Fig. 6 is a part plan, part sectional view of the match delivery mechanism, along the line 6—6 of Fig. 5; and

Fig. 7 is a diagrammatic view of the wiring circuit, with parts of the mechanism being shown diagrammatically.

My new and improved vending apparatus comprises a suitable frame 10, in which is secured a plurality or battery of vertically extending channel members forming compartments 12, 12, into which are placed the various commodities to be dispensed by the mechanism. As will be seen by reference to Figs. 1 and 3, the battery of compartments 12 extends vertically of the device, and terminates at the base at a point above and in spaced operating relation to my article ejecting mechanism 14, and a chute or slideway 16, down along which the ejected articles pass into the delivery mouth 18, from where they may be removed by the operator.

As will be seen by reference to the wiring diagram, Fig. 7, the apparatus is connected to a suitable source of current as at O. The current, passing through all "made" points, extends to the coin registers R, the counting mechanism M, the selecting mechanism S, the solenoids, the motor T and the locking mechanism L, although the various circuits cannot be "made" to cause actuation of the various parts of the mechanism until a sufficient number and value of genuine coins or checks are deposited.

As the checks or coins are deposited within my apparatus, they are first tested for genuineness. After passing through this test, the checks or coins drop or roll down chutes wherein, in accordance with their number and value, they register to energize a counting mechanism. The desired selector button may then be manually actuated by the operator, and, if a sufficient number of checks or coins has been deposited and registered by the counter, the button is locked, an electric motor is energized to eject the chosen article, the coins are dropped into a receptacle, the button unlocked, the counting mechanism reset, and the apparatus restored to its original condition.

The registering and counting apparatus

While my mechanism may be arranged to operate on a variety of coins or checks of different values, the present embodiment of my invention has been arranged to handle two coins; the five-cent nickel piece, and the ten-cent silver piece.

Two separate chutes are provided, the mouths or entrances to which may be placed in any suitable location on the mechanism but preferably at the upper portion thereof, so that the coins may pass by gravity down through the apparatus with the least amount of difficulty. Two coin chutes 20 and 22 are provided; chute 20 of size sufficiently large to receive the five-cent nickel pieces, and chute 22 to receive the ten-cent piece.

A conventional testing device 24 (not shown in any detail) for testing the genuineness of the checks or coins deposited is mounted in each of chutes 20, 22, near the entrances thereof so as to test the coins or checks. If the checks or coins are found to be spurious, they are either by-passed out of the apparatus forthwith, or else they may be returned to the depositor through slide-way 16, or deposited in a suitable receptacle. In any event, spurious checks or coins are prevented from reaching the registering part of my apparatus.

While separate chutes or slides 20, 22 are provided for the reception of the coins of different denomination, each with a separate entrance, the two chutes merge into a single chute 26, the bottom portion 28 of which is disposed above and in spaced relation to the temporary receptacle, 30. My counting mechanism M is set to operate in units of five cents each, and chutes 20, 22 are provided with suitable registers responsive to the action of the coins or checks passing therethrough. Chute 22, for the silver ten-cent coins, has two registers 34, 36. One register 34 is placed in chute 22 below the coin tester 24 and above the point at which chute 20 merges with chute 22, and the second register 36 is mounted beneath the point at which chute 20 opens into chute 22. Thus, as a genuine ten-cent silver coin is deposited in chute 22 and passes through the coin testing device 24, it successively contacts registers 34 and 36. As a five-cent nickel coin is deposited in chute 22, and passes the tester 24, it drops down chute 20 into portion 26 thereof and actuates only one register 36. Thus, the ten-cent piece, comprising two five-cent units actuates two registers; the five-cent coin but one.

My counting or totalizing mechanism M comprises a circular wheel 40 mounted on a shaft 42 secured to the side wall of frame 10. A spiral, coiled spring 44 is secured by its ends to shaft 42 and wheel 40, normally urging wheel 40 to rotate on shaft 42 in a counter-clockwise direction (see Figs. 2 and 7). A portion of the periphery of wheel 40 is notched to form a plurality of teeth 46 pointed in a counter-clockwise direction. A double-toothed escapement 48 is provided, mounted above and in operative relation to the toothed portion of wheel 40, on a pin 50 secured to the side wall of frame 10. One end 52 of escapement 48 is pivotally secured to the end 54 of plunger 56 protruding from a solenoid 58 in the circuit of registers 34, 36. On one side of wheel 40, on the body thereof, I mount a pin 60 which projects outwardly at right angles to the plane of wheel 40. Thus, when register 34 is actuated, contact is made at 35 and the solenoid 58 energized. As solenoid 58 is energized, its plunger 56 is raised upwardly, carrying with it the end 52 of escapement 48 and disengaging inner escapement tooth 62 from wheel 40. Wheel 40, thus released from the restraint of the escapement, is spring 44 urged forward, counter-clockwise, until the outer escapement tooth 64

stops same. As the contact at 35 is broken after the passage of the coin, solenoid plunger 56 drops down, carrying with it the escapement 48 pivoted on pin 50, until the inner escapement tooth 62 drops into and engages the next one of teeth 46 in the wheel 40. When register 36 is actuated by the passage of a coin and contact made at 37, solenoid 58 is again actuated and wheel 40 is moved forward another tooth-distance, and so on with each actuation of registers 34, 36. It will thus be seen that as each five-cent unit is registered, wheel 40 moves along a counter-clockwise arc one tooth distance.

At the present time, cigarettes are priced at fifteen cents (three units) or twenty cents (four units), and my counting mechanism is calibrated, and the selecting and ejecting mechanisms are set to operate, either for a three- or four-unit sale. It will be obvious that my wheel can be modified to operate for any desired number of units other than three and four.

My counting unit M has as a part thereof a group 66 of three contact blades 68, 70 and 72. The middle blade 70 is provided with contact points on both sides, and the inner blade 68 and the outer blade 72 are provided with contact points on their inner sides opposing the contacts on blade 70. When my counting mechanism is in its "at rest" position, as shown in Figs. 2 and 7, pin 60 on wheel 40 is spaced away from the contact blade assembly 66. Solenoid 58 is open and its plunger 56 is in the down position causing a locking engagement between escapement tooth 62 and wheel teeth 46 restraining wheel 40 against any movement. Counter-clockwise of this point of engagement, a sufficient number of teeth 46 must be provided to permit engagement of the wheel by escapement tooth 64 when the solenoid is energized, and clockwise of the point of engagement, a predetermined number of teeth 46 are formed in wheel 40 in accordance with the price-number of units of the articles disposed within the apparatus. My present embodiment is set to operate for a maximum of four units, and wheel 40 must, therefore, have at least four teeth clockwise of the original point of engagement by escapement 48. Each time solenoid 58 is energized, pin 60 moves with wheel 40 one tooth distance counter-clockwise. The third time pin 60 is thus moved, it bears against contact blade 70 and brings same into contact with blade 68. The circuit is thus completed to blade 90 of the selecting mechanism S (Figs. 2 and 7). The next actuation of wheel 40 carries pin 60 and blades 68 and 70 against blade 72. When this occurs, the parallel circuit is completed through to blade 92 of the selector set S. If any additional coins are deposited within the chutes, they will, if genuine, actuate registers 34, 36 and cause solenoid plunger 56 to rock escapement 48. However, due to the spring pressure of contact blades 66, wheel 40 will be prevented from moving further in a counterclockwise direction any substantial distance beyond the point at which pin 60 has brought about contact between blades 68, 70, 72.

It will thus be seen that the selecting mechanism S cannot, in any manner, be effectively operated before the counting mechanism M has been "set" by the deposit of a sufficient number of genuine coins or checks. If only three genuine coin units have been deposited in and registered by the apparatus, only one part of the selecting apparatus is energized, and only those commodities priced at three units may be se-

lected. It is only when four coins or check units have been deposited in and registered by the counting mechanism that the other part of the selectors is energized. At that time, either the three-unit or four-unit selector elements may be actuated to eject one of the commodities within the apparatus. In similar fashion, my mechanism may be modified to handle commodities priced at three or four different unit prices.

The selector mechanism

My selector mechanism is disposed within a small housing 78 which is mounted on and extends across the entire width of the frame 10. The front of housing 78 may be secured to the back of the front panel of the frame, and the open back of the housing may be as closed by panel 80. A plurality of buttons 82 are provided, one for each of compartments 12, mounted in aligned relationship to these channels 12, 12. Buttons or selectively operable elements 82 are normally urged outwardly from housing 78 by the action of a coil spring 84 bearing against the inside of the button head and back plate 80, and the buttons may be pushed inwardly only against the tension of this spring 84. A suitable locating pin 86 may be provided, mounted on plate 80, extending into coil spring 84, which pin serves to locate spring 84, to limit inward movement of the buttons 82, and to keep the spring from buckling, etc.

The front panel of the cabinet and the front of housing 78 are provided with suitable registering apertures, through which the front ends of the buttons 82 project. Each button is provided, rearwardly of the circular projecting end, with a bifurcated top platform 74, and a lower slide platform 76. A pair of stepped fingers 88, 88 are provided, projecting from the ends of the legs of platforms 74 (for purposes to be explained below), and a centrally located and downwardly projecting lip 94 constituting an abutment is formed at the rear end of the slide platform 76 on the bottom of each button 82 (see Figs. 3 and 4). Back panel 80 is suitably apertured so that the hooked fingers 88, 88 and projecting lip 94 may reciprocatably slide back and forth therethrough under manual urging inwardly and spring-84 pressure return movement. A shoulder 96 is formed on each button between the platform 74 and the circular tip which, bearing against the housing wall, limits the return movement of the buttons under the urging of the interiorly seated springs 84.

As will be seen in Fig. 4, one of the legs of the bifurcated button platform 74 is shouldered inwardly forming a locking catch or hook 100, and an angled track or path 102 between the spaced platform legs. A button holding bar 104 is provided, consisting of an elongated rod mounted in housing 78 so as to slide back and forth therewith. Bar 104 has formed thereon, at spaced distances corresponding to the distance between buttons 82, a number of upstanding fingers 106, one for each button, and the bar is so disposed within housing 78 that fingers 106 normally are opposite to and register with the openings into the trackways 102 of the buttons 82. When any button 82 is depressed and the locking bar 104 actuated the corresponding finger 106 engages catch 100 to retain the button in depressed position. A selecting rod 108, which may be formed of heavy gauge wire, is mounted within housing 78 in a space between the top of the button plat-

form 74 and the underside of the top of the casting. Rod 108 extends across the full width of the cabinet and is provided with a bent-over end portion 110 which extends out of the frame beyond the button battery and is disposed between the contact blades of the selecting mechanism. A collar 112 of a suitable insulating material such as rubber or the like is fitted onto this bent-over end 110, to prevent untoward contact between the blade sets. Platform 74 of each button 82 has formed therein a pair of spaced apart screw-threaded openings 119, 120, each of which is adapted to receive a pin 122 therein. Rod 108 has formed therein, as by bending or otherwise, a plurality of V-portions 124 serving as opposing camming portions, and the rod is so disposed within housing 78 that the V-portions extend over button platforms 74 with the apex 126 of the V-portion between openings 119, 120. Opposed to blade 90 of the selecting battery, there is disposed a contact blade 90a, and I provide a contact blade 92a opposed to blade 92. Blades 92a and 90a are wired through to solenoid 114 mounted below lock bar 104. Plunger 116 of the solenoid 114 is spring-linked to a hook member 118 integral with and depending from the button lock bar 104.

Thus, when pin 122 is inserted in opening 119 of button plate 74, and button 82 is pushed inwardly, the camming action of the angled leg of the V-portion 124 will cause selector rod 108 to shift to the right, pressing contact blades 92 and 92a together, completing the circuit through to solenoid 114. If pin 122 is inserted in the opening 120 on the other side of the V, pushing button 82 inwardly would, in similar manner, cause rod 108 to shift to the left, and press together blades 90 and 90a and complete the circuit through to solenoid 114. When the solenoid is thus energized, plunger 116 is drawn into the solenoid, carrying along with it button lock bar 104. Thus, referring to Fig. 4, as button 82 is pushed inwardly (assuming a sufficient number of genuine coins or checks to have been inserted to energize counting mechanism M and blades 90, 92 of the selecting mechanism S) lock bar 104 will be shifted to the right, and finger 106 will slide into the angularly related portion of trackway 102 behind extension 100, preventing button 82 from sliding back under the influence of spring 84. As lock bar 104 is shifted also, the tip end 128 extending out from one end of housing 78 makes contact between the blades of the locking mechanism L by bringing same together, and completes the circuit through the motor T, which, in turn, operates the article ejecting mechanism. Pin 122 may be placed in only one or the other of platform openings 119, 120 at a time, and not in both simultaneously. If placed in both of openings 119 and 120, the pins would constitute a stop against inward movement of button 82 under manual urging.

I also provide means whereby after a button has been pushed in and locked in the "in" position, all the other buttons are prevented from being pushed inwardly. On the floor of housing 78 I provide a number of substantially rectangular flat plates 130, disposed side by side in abutting relationship, forming a slide. The abutting edges of plates 130 are rounded off at the forward ends thereof, and the mouths 132 thus formed are adapted to receive a pointed nose 134 formed on the underside of each button. The two endmost plates 130 are each provided with a pin 136 which projects down and out of

housing 78 through a suitable slot in the floor thereof. A pair of hooked members 138 receive the pins 136 within the longitudinal slots therein, as seen in Fig. 1. The members 138 are engaged with the floor 78 riding in slots formed therein and are urged towards each other by springs to maintain the plates 130 normally in engagement with each other and in operative relation to the several noses 134. When any button 82 is depressed portions of the plate assembly are spread apart or moved as a whole in one direction or the other to place the plates 130 in position serving as stops to prevent depression of the remaining buttons, the contiguous walls of the chassis serving as stops limiting the movement of the retaining members 138.

The motor and its circuits

After a sufficient number of genuine coins or checks have been deposited within the chutes and registered by my counting mechanism M, and the desired article chosen in accordance with the number of units counted, the motor circuit is completed through the action of lock bar 104 bearing against the opposed contact blades 140, 142 of the locking battery L and bringing same together. The electric current is open to blade 142 when the machine as a whole is plugged or connected to any suitable source of electricity, and the opposed blade 140 is wired through to motor T (see Fig. 7). The current is also open to motor T, and when contact is made between blades 140, 142, the circuit of the motor is closed and the motor begins to function.

Motor T, which operates the ejecting mechanism, may be disposed on the floor of frame 10 midway between the sides thereof, and is connected by appropriate gearing 144 to a shaft 146 extending the width of the casing, and projecting out from the frame at both sides thereof (see Fig. 1).

Shaft 146 is composed of a central portion 148 of solid bar material and a pair of side portions 150, 150. The central portion is connected to and driven by motor T through gearing 144, and the side portions are secured to the central portion by appropriate sleeves 152, 152. The side portions 150, 150 are composed of a flexible shaft material, sufficiently rigid to transmit the drive yet flexible enough to withstand working stress and strains. The outer ends of shaft portions 150, 150 are mounted in bushings 154, 154 and project out from the side walls of frame 10, to each of which ends is secured a crank 156, 156. Cranks 156, 156 are secured onto the ends of shaft 146 in perfect alignment so that as shaft 146 is rotated by the motor, the cranks will be driven simultaneously and arms 158, 158 of the cranks will move around in alignment.

Motor T may be constructed to operate at two speeds; a regular speed for operation of the ejecting mechanism, and a slower speed for restoral of the mechanism to "ready" position. Shaft 148 has mounted thereon, for rotation therewith, a cam 160. I mount, in operative relation thereto, two sets of opposed contact blades P. As shaft 148 is rotated, cam 160 is carried around, bears against and brings the blades of one set 162 together. The contact thus made through resistance 164 reduces the speed of motor T, and as the movement of cam 160 continues, blades 166, 166 are brought together, causing the closing of a local circuit through the motor to insure continued operation thereof after the other motor circuit is opened at 142.

At one side of shaft 146, a driving gear 168 is mounted thereon for rotation therewith. I provide a short stub shaft 260 and mount same for rotation within the same side wall of frame 10 as gear 168 is located. I mount a driven gear 262 on shaft 260 in mesh with driving gear 168 of the main drive shaft. The inner face of gear 262 has a pair of cams, 170, 170 thereon diametrically opposed to one another, and it is this gear 262 and cam 170 arrangement which functions not only to unlock the button holding arrangement, but also to break the motor circuit, and also to drive a second dispensing mechanism, as will be explained in detail below. A depending plate 172 is secured to the underside of housing 78, and a hooked bar 174 is pivotally secured thereto (see Fig. 1). The upper end 176 of bar 162 bears against a finger 178 which is formed as an integral part of lock bar 104, and when lock bar 104 is shifted to the right by the action of solenoid 114, it shifts with it the upper end 176 of bar 174. Bar 174 is centrally pivoted (see Fig. 1) and movement of the top end 176 to the right will cause the other and hooked end 180 to shift to the left, against gear 262. As gear 262 is rotated by driving gear 168, cam 170 will engage the hook end 180 and cause it to shift to the right. This shift will cause the top end 176 to move to the left, and bearing against finger 178, to carry bar 104 along with it. The withdrawal of lock bar 104 will relieve the pressure of tip 126 against the contacts at L and will permit blades 140, 142 to spring apart, and thereby break the motor circuit. The return movement of lock bar 104 will simultaneously cause a withdrawal of the holding fingers 106 from under hooks 100, and will permit the locked button 82 to slide back out under the urging of spring 84.

The ejecting mechanism

My ejecting mechanism 14 comprises a carriage or support 182 mounted in the lower part of frame 10 for reciprocating movement back and forth in operative relation to the article containing compartments 12. Carriage 182 comprises a channel member 184 which extends across the width of the casing. The ends of the channel project through arcuate openings 186 formed in the sides of the frame where they are secured to supporting arms 188, 189, each of which is pivotally mounted near the floor of the casing, as at 190, 190.

Channel member 184 may be formed of a light gauge metal, stamped or otherwise formed so that it is substantially U-shaped in cross-section, having a front portion 192, a short top portion 194 angled over inwardly, a bottom portion 196 parallel to top 194, an angled portion 198 and a back portion 200 parallel to front 192. Vertically aligned apertures 202, 204 are formed in top and bottom portions 194, 196, respectively, and a pair of openings 206, 208 are formed in the upper parts of front and back portions 192, 200, respectively, in line with openings 202, 204. Channel member 184 is so disposed within the device, that the aligned openings 202, 204, 206, 208 are disposed opposite each button 82 and hence in line with each article containing compartment 12. A vertically slidable plate 210 is mounted in openings 202, 204, and a horizontally slidable plate 212 is mounted in openings 206, 208. Plate 210 is suitably apertured, as at 214, in order that horizontal slide 212 may pass therethrough (see Fig. 3). A U-shaped member 216, the opposed ears of which are suitably apertured, is

10 mounted on angled portion 198 in line with the slide openings, and a right-angled level 218 is pivotally mounted therein by means of an elongated pin 220 passing through all the apertured 5 ears of the U-yokes or sockets 216 and the angles of the levers. One arm 222 of lever 218 projects through an opening 224 in slide 212, and the other arm 228, at right angles to arm 222, projects through an opening 228 in vertical slide 210. A 10 coil spring 230 is placed around arm 226 and locked between the angle of the lever and a spring plate 232 bearing against slide 210.

As will be seen by reference to Fig. 2, each 15 channel supporting arm 188 is vertically slotted, as at 234, and the crank pin 158 extends thereto. Thus, as shaft 146 is rotated by motor T, crank pins 158 will be rotated along with it and the carriage 182 will be moved back and forth in an arcuate path limited only by the length of 20 cranks 156, 158 and the arcuate openings 186 in the side walls of the casing through which the channel support 184 extends.

Referring now to Fig. 3, the dotted line position 25 of button 82 indicates the point of extension at which it is locked after being manually pushed inwardly, and the abutment lip 94 is extended along with it. The normal portions of slides 210, 212 are shown in heavy lines, and as carriage 182 is moved forward, the leading end 236 of slide 212 30 is brought into contact with button lip 94. The continued forward movement of carriage 182 against the locked and immovable button will cause slide 212 to be shifted backwardly. Lever arm 222, engaged with slide 212 will be carried 35 along with it in its rearward movement, and the other lever arm 226, pivoting on pin 220, will shift upwardly, raising vertical slide 210 to the dotted line portion of Fig. 3. Slide 210 rises to its 40 topmost position when carriage 182 is at the limit of its forward movement. As carriage 182 starts its return movement, the top portion 238 of slide 210 engages the front end of the packaged commodity resting on the inturned bottom edges 240 of compartments 12 and pushing same before it, 45 carries the commodity through the opening 242 in the rear of the channel into chute 16, along which it slides down into the delivery mouth 18, from which it may be removed by the operator.

As carriage 182 approaches the peak of its rearward movement, the rear end of slide 212, 50 extended as a result of contact with button lip 94, is brought against wall 244 forming the front of chute 16 and serving as a common abutment for returning the several members 212 to normal position and retracting the members 210 with a 55 snap action, as shown in full lines at Fig. 3.

A slightly tensioned spring arm 246 is mounted 60 on the back of the casing, opposite each opening 240, in order that the packaged articles shifted from the channels 12 by the vertical slide 210 65 may be directed into the delivery chute 16.

Means are provided to lock the button of each 70 channel from which all the commodities have been dispensed. Referring to Figs. 3 and 4, a pair of bars 248, 248 will be seen at the bottom of each compartment 12. The bars 248, 248 are pivoted off-center, as at 250, to each compartment wall, below the platform portions thereof, so that normally the longer portions 252 thereof, reaching 75 forwardly towards the button assembly, would drop down, raising the opposite shorter arms 254 into the compartments 12. The forward reaching ends of each pair of the longer portions are connected by a cross-bar 256, and when the longer portions are in the down posi-

tion, the cross-bar drops down onto and rests within and against the stepped portion 258 formed at the end of the fingers 88, 88, of the bifurcated upper button platform 74. Bars 248, 248 are formed of very light metal or other suitable material. Thus, the weight of the commodities which may be disposed within compartments 12 need not be considerable in order to depress the shorter arms 254, 254, and elevate the longer arms 252, 252 and thus raise cross bar 256 above the level of button 82 and out of engagement with the stepped portion 258. When all the commodities within any particular compartment have been disposed therefrom, the weight of the longer arms will be sufficient to cause a dropping down of the cross bar 256 and the presentation of a stop against any inward movement of the particular button 82 opposite the compartment.

The supplementary dispensing mechanism

Associated with my main dispensing mechanism, I provide a supplemental dispensing device. I have described the present embodiment of my invention as adapted for dispensing cigarettes, and in connection therewith, I have devised a supplemental mechanism for dispensing associated articles, as match booklets or boxes or the like. It will be obvious that this supplemental mechanism may be used for dispensing any commodity, and one not necessarily associated with the contents of the main magazines. I mount the short stub shaft 260 in the frame side wall, and secure thereon the driven gear 262 in mesh with the driving gear 168 on the main drive shaft 146 as outlined above. To the other end of stub shaft 260, extending outside of the frame side wall, I secure a crank 264. An elongated link 266 is secured to the end of the crank 264, and to the other end of link 266, reaching vertically upwards, I connect one end of an angular lever 268 by means of a yoke 270. The other end of the angled lever 268 is link-connected by a short bar 272 to a sliding platform 274 having raised lips 276, 276 at the front and rear thereof.

I provide a pair of spaced-apart magazines 278, 278 on the side of frame 10, the bottoms of which open onto the match delivery slide 274. The bottom edges of the magazine side walls are turned inwardly to form platforms 280, 280 upon which the stacked contents of the magazine are rested. The magazines 278, 278 are spaced-apart as above noted, and a chute 282 is provided within the space and underneath the magazines to direct the contents out into delivery mouth 18. The lip portions 276, 276 of the slide member extend upwardly above the platform 280 edges. The magazine and slide assembly are supported by a suitable bracket 284 secured to the side wall of the frame. The ends of the front lip 276 are provided with angled leading portions 286 for purposes to be explained below.

The ratio of driving gear 168 to driven gear 262 is 2:1; that is, a complete revolution of gear 168 will cause a 180 degree turn of the driven gear 262. Each complete turn of drive shaft 146 will cause a half circle rotation of gear 262 and stub shaft 260 and crank 264. The clockwise rotation of crank 264 through a 180 degree arc will cause a raising of link 266, a pivoting of lever 268 about its axis at 269, and a forward sliding movement of slide platform 274. The rear lip 276, as slide 274 moves forward, will engage and carry along with it a match booklet, as 288, or other commodity, until it drops down into the intermagazine space along chute 282 and down and

out into delivery mouth 18. As slide 274 moves forward, the angled heads 286 of the front lip 276 will glide in under the bottommost of the stacked commodities in the other of compartments 278, and raise same slightly until the front end of the slide moves past the edge of that magazine and permits the commodities to drop down onto supporting edges 280, 280 again. The next half circle turning movement of shaft 260 will draw link 266 down, and through angled lever 268 will cause slide 274 to move back, carrying along with the back of front lip 276 a commodity from the other magazine until dropped down onto chute 282. In this manner, I am enabled to dispense commodities from two different sources. The commodities may, but need not be, associated in use. The time cycle is such that for each article dispensed from the main magazines 12, an article is dispensed from the magazines 278 by means driven by the main dispensing means.

The check or coin receptacles

Passing down through chutes 20, 22 into the temporary coin or check receptacle 30, the coins are supported therein by a pair of springs 300 urged together pivoted leaves 302, 304, interlocked at the bottoms thereof, as at 306. After a number of coins have been deposited within my device, and at any time before a suitable button 82 is actuated to start the motor T, the coins are held, so to speak, "in suspension" and they may be retaken or recalled by the operator. The construction and operation of this portion of my device is as follows:

A coin return lever 308 is provided, suitably located on the frame 10 so that same may be readily grasped. If it is desired to recall the checks or coins deposited, lever 308, pivoted at its far end at 310, is pulled downwardly. A link 312 is connected at one end to lever 308 and at its other end to an angled lever 314. The downward movement of lever 308 is thereby communicated to lever 314, which is pivoted at 316, and the other and angled arm 318 thereof is provided with a pin 320 extending outwardly from arm 318 and into a slot 328 in a sliding member 322. This sliding member 322 is mounted on frame 10, and is held thereon by headed pins 324, 326 passing through elongated slots 328, 330 respectively. The slide 322, at its other end, is provided with an integral bent-over extension arm 332, and the end of which is forked, as at 333 to receive one of the pins 334 holding one end of spring 300. The other end of spring 300 is secured to a pin 336, and the side wall 338 of receptacle 30 is provided with a pair of arcuate notches or tracks 340, 342 on opposite sides thereof, within and along which pins 334, 336, respectively, may be shifted.

As lever 308 is depressed, the vertical movement is translated to circular movement, because the angled lever 314 is pivoted about its axis at 316. Pin 320 is carried in a clockwise direction, carrying slide 322 to the left. Extension 332 is moved along with slide 322, and carries pin 324 with it. The opposite pin 336 is held captive in track or notch 342 and spring 300 is extended, relieving the spring restraint on leaf 302, holding same interlocked with leaf 304. Pivoted leaf 302, under the weight of the coins, drops down to a vertical position over the coin by-pass 344, and the coins may drop through and into the delivery mouth 18, which may be in communication with that portion of the re-

ceptacle 30. Other provision may be made for a coin return chute, as desired.

After the required number of coins have been deposited, and the motor T is started, crank arms 158 start their clockwise rotation, carrying supporting arms 188 along therewith. On the outside of frame 10, in line with the arm 188 on the coin receptacle side thereof, I mount a horizontally sliding rod 346 by means of a pair of pins 348, 348. Rod 346 is slotted to receive the pins 348, and is provided with an angled upstanding arm 350 which bears against spring leaf pin 338. As the supporting arm 188 moves backward in its article ejecting phase of movement, the end of rod 346 is engaged thereby and slid back carrying along with it the arm 350, which then contacts and bears against spring pin 338. The other end of spring 300, seated in pin 334 held captive in track or notch 340, is fixed and the movement of pin 338 extends spring 300 and removes the tension support from under leaf 304, permitting same to pivot downwardly to a vertical position under the weight of the coins, over a suitable permanent receptacle 352, the entrance 354 to which is directly underneath leaf 304.

Thus it will be seen that in my mechanism, the coins or checks may be recalled before operation of the machine, or received in a permanent receptacle upon operation of the machine.

Resetting the counting and registering mechanism

It is of the utmost importance, in vending machines of the character described, to guard against and prevent, if possible, fraudulent manipulation thereof. Referring to Fig. 2, it will be seen that I have made provision against any manipulation of the coin return mechanism after the motor circuit is started and in other ways prevent misuse of the apparatus.

Pin 324, on which horizontally sliding rod 322 is mounted, has pivotally secured thereto an angled lever 356. Lever 356 has a long, normally vertically depending arm 358, and a shorter, right angled horizontally disposed arm 362. The extreme end of arm 362 is pivotally connected to an elongated rod 364 which extends up to and engages counting wheel 40. The upper end of this vertically extending rod 364 is slotted at 366 to receive a pin 368 secured to and projecting outwardly from wheel 40. In normal, unset position, the respective parts of my apparatus are as shown in full lines in Fig. 2.

Pin 320, on lever 314, also bears against arm 362, normally resting at the bottom of a notch 370 formed in arm 362, and the lever arm 318 is provided with an angled extension 372 in line with the main part of lever 314.

Thus, if after a number of coins or checks have been deposited in the device, and registered by the counting wheel 40 moving several notches in a counterclockwise direction and bearing against the contact battery 66, completing the circuit through to the selecting mechanism, it is desired to recall the coins, downward movement of coin return lever 308 will cause several things to happen. First, the leading end of extension 372 will swing forward within the channel formed by the frame wall and a spring leaf 374 which is spaced therefrom, and across the opening 376 in the side wall of the frame through which the tip end 128 of lock bar 104 projects to make a contact at L between blades 140, 142. Extension 372 will block off opening 376 and thus prevent bar 104 from passing through opening 376 to bear

against and make contact between the blades 140, 142 and thereby completing the motor circuit. Thus, the first thing to happen on actuation of return lever 308 is to prevent starting of the motor T. If, after the coins or checks have been deposited and a button 82 is pushed inwardly to complete the circuit through to motor T through the action of lock bar threading through opening 376 and making contact between blades 140, 142, it is attempted to actuate return coin lever 308, the projecting end of rod 104 through opening 376 will act as an effective stop against any movement of lever 314 acting on coin return slide 322. Only one thing can happen. If the coins are returned, the motor circuit cannot be completed. If the motor circuit is completed, the coins cannot be recalled. Both events, in the absence of any physical damage to the mechanism, cannot take place.

20 The second thing that occurs is that pin 320, swinging through a clockwise arc, depresses lever arm 362 by riding up the inclined side of notch 370, and causes rod 364 to be drawn downwardly thereby turning counting wheel in a clockwise direction and withdrawing pin 60 from relieving the pressure of said pin 60 against the contact blade battery 66.

25 The third thing to occur is the return of the coins via the action of slide rod 322 on spring leaf 302.

30 The counting mechanism is also reset when the motor T is actuated to and does move through the article ejecting phase of its cycle. Crank arm 158 rotates in a clockwise direction, and 35 crank 156 is of such length that when it sweeps around, arm 158, projecting outwardly from the crank, will engage the vertically depending crank arm 358 and carry same upwardly, into the position shown in dotted lines in Fig. 2. Pivoting 40 counterclockwise about its axis 324, the shorter, horizontally extending arm 362 will carry rod 364 downward along with itself and with its engagement to counting wheel 40 by pin 368, will cause wheel 40 to be pulled around and back to its unset 45 condition, in this way also relieving the pressure of wheel pin 60 against the contact blade 66.

Having described my invention, what I claim and desire to secure by Letters Patent is:

1. A check controlled apparatus comprising article dispensing means including an electric actuator, means including parallel circuits for controlling the operation of said actuator, contact means for closing the circuits at certain points, juxtaposed contacts in said circuits at other points, and means coacting with said contacts to selectively actuate the same, said last mentioned means being movable in one direction to close the circuit of one setting and in the opposite direction to close the circuit of another setting.

50 2. A check controlled apparatus comprising parallel circuits for controlling the operation of said apparatus, juxtaposed contact blades for setting said circuits for operation, a member advanced step-by-step to close successively the

55 blades of one circuit upon a given advance and the blades of another circuit upon an additional advance, electromagnetic means for actuating said member including a circuit having portions in parallel, coin actuated contacts in said parallel portions to be actuated by coins of different denominations, the contacts for the coin of smaller denomination being disposed below and in the path of the coin of larger denomination, and means for selectively controlling said first-mentioned parallel circuits at other points thereof.

3. A check controlled apparatus comprising dispensing means including an electric actuator, means including circuits for controlling the operation of said actuator, means for closing said circuits at certain points, actuating means therefor including coin responsive means to condition each circuit for operation in response to the insertion of a different predetermined amount of coins, means for controlling said circuits at other points, a transversely disposed member movable in opposite directions to actuate said circuit controlling means for completing one circuit or another, selective operable elements, and means upon each element and said member coacting to determine the direction of movement of said member upon actuation of each element.
4. A check controlled apparatus comprising dispensing means including an electric actuator, control circuits for said actuator, coin controlled means for setting said circuits for operation one in response to a given coin amount inserted and another in response to a different given coin amount, sets of blade contacts in said circuits arranged contiguous to each other in spaced relation, selectively operable elements, a member extending along said elements and having a portion extending between said sets of contacts to actuate one or the other according to the direction of movement of the member, and means upon each selective element and the contiguous portion of said member coacting to actuate said member and determine the direction of movement thereof.
5. A check controlled apparatus comprising means for dispensing articles at different prices, coin controlled means for conditioning said dispensing means for operation at one price or another, means to cause operation of said dispensing means under one condition or another, selectively operable elements, a member extending transversely of said elements for actuating said last-mentioned means and having forwardly converging opposing cam portions contiguous to each selective element, and a pin on each element adapted to be removably engaged with said element in either of two positions for coaction with one cam portion or the other.
6. A check controlled apparatus comprising means for dispensing articles at different prices, coin controlled means for conditioning said dispensing means for operation at one price or another, means to cause operation of said dispensing means in accordance with one condition or another, selectively operable elements, a member extending transversely of said elements for actuating said operation causing means, and having opposing cam portions facing each selective element, and means on each selective element adapted to coact with one or the other of the contiguous cam portions to move said member in one direction or the other.
7. A vending apparatus comprising a plurality of article compartments, a support extending transversely of said compartments and having depending arms pivotally supporting the same for swinging movement relative to said compartments, each of said arms having longitudinally extending slots therein, a motor, a transverse shaft driven by said motor, cranks at the ends of said shaft having pins riding in said slots for swinging said support, ejecting elements movably mounted on the support for projection into and retraction from article ejecting position, and means under selective control for projecting said elements.
8. A vending apparatus comprising a plurality of compartments, a movable support at one end of said compartments movable forwardly and rearwardly, an ejecting member for each compartment slideable vertically on said support, a member disposed horizontally on said support for sliding movement transversely to each ejecting member, means for transmitting movement of said horizontal member to said ejecting member, means for actuating said support, depressible selector elements each opposing a horizontal member to actuate the same upon forward movement of the support, and means engaging said horizontal member upon rearward movement of the support to actuate the horizontal member in the reverse direction.
9. A coin controlled apparatus comprising a coin receiving receptacle including a pair of plates pivotally supported at the upper edges and extending downwardly towards each other into closing relation, spring connected members engaging the plates to retain the same closed, said members being slidably supported for movement to and from said plates independently of each other, means for moving one of said members to release one of said plates to cause the same to open for the return of coins to the operator, and means to move the other member to release the other plate for the delivery of coins to be retained.
10. A coin controlled apparatus comprising actuated means, a control member therefor advanced step-by-step, coin controlled means for actuating the member, a coin receptacle adapted to be operated to return coins and retain coins, means for resetting said member including a link having a slot and pin connection thereto, a bell-crank having one arm connected to said link at the opposite end and the other arm in the path of a movable part of said actuated means, said first named arm having a notch, actuating means for returning the coins including a lever having a pin engaged in said notch, and a member engaged by said pin for operating said receptacle.
11. A vending apparatus comprising a plurality of compartments for articles to be dispensed at different prices, a support mounted for movement relative to said compartments, ejecting elements each associated with a corresponding compartment and movably mounted upon said support to be projected and retracted to dispense an article, an electric motor for actuating said support, circuits for said motor, means responsive to the action of coins in different amounts corresponding to the said prices for setting one circuit for operation in dispensing an article at one price and another circuit for operation in dispensing an article at a different price, contact means for closing one circuit or another at other points, and means selectively operable to render any ejecting element operative to dispense an article of one price or another upon actuation of said support and to actuate said last-named means to close the circuit set for operation by the coin amount corresponding to the price of the article selected for dispensation.
12. A vending apparatus comprising compartments for articles to be dispensed at different prices, means for dispensing the different articles including ejector elements each adapted to be moved into and from ejecting position relative to a corresponding compartment, an electric motor for actuating said dispensing means, parallel circuits for controlling the operation of said motor, contact means for closing the circuits at certain points, means responsive to the action of

coins in different amounts corresponding to said prices for actuating said contact means to set one circuit for operation in dispensing an article of one price and another circuit for operation in dispensing an article of a different price, juxtaposed contacts in said circuits at other points, means coacting with last-named contacts movable in one direction to close one circuit and in the opposite direction to close another circuit, and means selectively operable to render any ejector element operative to dispense an article of one price or another upon actuation of the dispensing means and operatively coordinated with said oppositely movable means to actuate the same in a direction to complete the circuit set by a coin amount corresponding to the price of the article selected.

13. A vending apparatus comprising a plurality of article compartments, a support movable relative thereto, ejector elements on the support for movement into dispensing position, means associated with each ejector element and movably mounted on the support for translating movement to the ejecting element into dispensing position upon movement of the support, a motor including a circuit for actuating said support, coin controlled means for setting said circuit for operation, means movable into position selectively to be engaged by any of the said translating means upon actuation of said support for projecting the corresponding ejecting element, and means controlled by said last-named means for completing the circuit of the motor.

14. A vending apparatus comprising a plurality of article compartments, a support mounted for movement relative to said compartments, article ejecting elements each movably mounted on said support and associated with a corresponding compartment to be projected into and retracted from dispensing position relative thereto, means mounted on said support for movement relative to each ejecting element for translating movement thereto upon actuation of said support, selector elements each associated with a last-named means and adapted to be positioned to be engaged thereby upon movement of said support to project said ejecting element through the action of the translating means, means for actuating said support, and means controlled thereby for locking the selector element when positioned to be engaged.

15. A vending apparatus comprising dispensing means, actuating means therefor, a control member advanced step-by-step for setting actuating means for operation, coin controlled means for actuating the member, means for selectively controlling said dispensing means and the operation of said actuating means, a temporary coin receptacle operative to return and retain coins, means for resetting said member including a link having a slot and pin connection at one end with said member, a bell-crank having an arm connected to said link at its opposite end and an arm in the path of movement of said dispensing means, means for actuating said receptacle to return coins including a member engaging said bell-crank to effect the resetting operation and a member movable into position to prevent operation of said selective controlling means, and means actuated by said dispensing means for operating said receptacle to retain the coins.

16. A check controlled apparatus comprising a plurality of compartments for articles of dif-

ferent prices, means for dispensing an article from any compartment, means responsive to the action of coins in different amounts for conditioning said dispensing means for operation at one price or another, manually movable selector elements for controlling said dispensing means to render the same operative to dispense an article from one compartment or another, a member extending transversely of said selector elements for movement in opposite directions, each selector element and the contiguous portion of said member having coacting means for actuating said member in one direction or the other according to the price of the article selected for dispensation, and means operated by one movement of said member or the other, to cause operation insuring the dispensation of an article at a price corresponding to the coin amount inserted to condition said dispensing means.

17. A vending apparatus comprising a plurality of compartments for articles to be dispensed, a support mounted for movement relative to said compartments, a separate ejecting element for each compartment movably mounted upon said support to be projected and retracted to dispense an article, an electric actuator for moving said support, means for supplying power to said actuator including a control circuit having a pair of contacts, and selectively depressible means operable to render any ejecting element operative to dispense an article from a selected compartment upon actuation of said support and to close said pair of contacts and thereby supply power to said actuator to move said support.

18. A vending apparatus comprising a plurality of compartments for articles to be dispensed, a support mounted for movement relative to said compartments, a separate ejecting element for each compartment movably mounted upon said support to be projected and retracted to dispense an article, an electric actuator for moving said support, means for supplying power to said actuator including a control circuit having a pair of contacts, and selectively depressible means operable to render any ejecting element operative to dispense an article from a selected compartment upon actuation of said support and to close said pair of contacts and thereby supply power to said actuator to move said support, means for locking said depressible means in its depressed position, and electromagnetic means forming part of said circuit for urging said locking means to operative position when said electromagnetic means is energized.

19. A vending apparatus comprising a plurality of compartments for articles to be dispensed, a support mounted for movement relative to said compartments, a separate ejecting element for each compartment movably mounted upon said support to be projected and retracted to dispense an article, an electric actuator for moving said support, means for supplying power to said actuator including a control circuit having a pair of contacts, selectively depressible means operable to render any ejecting element operative to dispense an article from a selected compartment upon actuation of said support and to close said pair of contacts and thereby supply power to said actuator to move said support, and means actuated by said actuator upon operation thereof for opening said circuit.

20. In a vending apparatus having a plurality of article compartments; a support mounted for reciprocating movement transversely of said compartments; article ejecting means for each

compartment comprising an individual ejecting member slidably mounted on said support for movement into and out of article ejecting position, an actuating member slidably mounted on said support and projecting therethrough, a lever pivotally carried by said support with one arm operatively connected to said ejecting member

and the other arm operatively connected to said actuating member, and means adapted to engage said actuating member to move the same as said support approaches each of its limits of movement.
